UNITED STATES PATENT OFFICE.

ALLEN J. FOWLER, OF LONDON, CANADA.

DESIGN FOR A LIQUID-FUEL AND AIR BURNER.

SPECIFICATION forming part of Design No. 35,428, dated December 10, 1901.

Application filed October 11, 1901. Serial No. 78,323. Term of patent 14 years.

To all whom it may concern:

Be it known that I, ALLEN J. FOWLER, a citizen of the United States, and a resident of the city of London, in the county of Middlesex, in the Province of Ontario, Canada, have invented and produced a new and original Design for Liquid-Fuel and Air Burners, of which the following is a specification.

Reference is had to the accompanying drawings, forming part thereof, wherein—

Figure 1 is a side elevation of a liquid-fuel and air burner, showing my new design. Fig. 2 is a plan view of same.

In said drawings, the numeral 1 designates the base; 2, the vaporizing-chamber; 3, the vapor -superheating chambers; 4, the air-superheating chamber; 5, the burner-pipes; 6, notches or recesses formed in the lower edge of, and 7, ornamental bands extending around, said vapor and air superheating chambers 3 and 4.

As shown in the drawings, the leading or material features of my design are, first, a vaporizing-chamber 2, surmounted by an air-superheating chamber 4, and both located between two vapor-superheating chambers 3, and, second, of ornamenting each of said vapor and air superheating chambers 3 and 4 with an ornamental band 7.

Having thus described my invention, what I claim as new, and desire to secure by Letters Patent, is—

The new and original design for a liquid-fuel and air burner substantially, as herein shown and described.

In testimony whereof I have signed my name in the presence of the two undersigned witnesses.

ALLEN J. FOWLER.

Witnesses:

P. J. EDMUNDS,
W. L. MOYER.
